UNITED STATES PATENT OFFICE

2,482,103

TYPING REPERFORATOR

Antonio P. Di Gregorio, United States Army,
Washington, D. C.

Application January 16, 1946; Serial No. 641,555

5 Claims. (Cl. 164—113)

(Granted under the act of March 3, 1883, as
amended April 30, 1928; 370 O. G. 757)

1

The invention described herein may be manufactured and used by or for the Government for governmental purposes, without the payment of any royalty thereon.

This invention relates to Teletype printing systems, and more particularly to improvements in typing reperforators used in such systems.

A typing reperforator is a motor driven mechanism for receiving messages over wires and recording the messages in both code perforations and typewritten characters on the same tape. Receiving units of this kind are particularly adaptable for use at message distribution centers because the perforated tape may be used to retransmit the message to one or more stations by means of another unit known as a transmitter-distributor, thus eliminating the necessity for manual transmission by direct keyboard or manual preparation of perforated tape. The typewritten characters on the tape facilitate identification and distribution of the message tape at the message center.

Typing and perforation occur simultaneously, but due to the fact that the platen is to the right of the perforation die block, characters are typed to the right of their respective perforations.

The printing operation is controlled by the operation of a main bail, and is independent of the punching operation for perforation. However, the freeing of the code bars, to enable the code bars to be positioned by the selector for various code signals, has, heretofore, depended upon the engagement of the main bail with a code bar locking lever. This dependence of the positioning of the code bars on the operation of the main bail is objectionable in that the main bail frequently becomes jammed and allows the code bar locking lever to prevent positioning of the code bars, even though the selector mechanism and perforating punch continue to operate. The jamming of the main bail causes messages to be mutilated and consequently delayed or even lost. This trouble is particularly serious in the case of monitoring reperforators used in semi-automatic teletypewriter systems. The monitoring machines are infrequently observed and several hours of monitor copy may be lost because of main bail jamming.

In the operation of punch selection on a typing reperforator, the downward stroke of the main bail clears the punch selection bell cranks from the code bars; then selection of code bars is made by the incoming signal, and finally, upward stroke of the main bail allows the bell cranks to fall in correct positions against the code bars. Jamming of the main bail causes the punch selection to remain cleared and results in the tape being continually perforated over and over with the same combination, and no printing. Jam-

2

ming of the main bail results from a number of causes, such as improper or lack of lubrication and adjustment of the main bail and associated parts, incorrect ribbon replacement, slightly worn main bail, broken main bail spring, failure of ribbon reverse mechanism, etc.

It is, therefore, an object of this invention to provide means to cause continual functioning of the code bar locking lever independently of the operation of the main bail to position the code bars in accordance with incoming signals and to cause the tape to be perforated accordingly.

A further object is the provision on a typing reperforator of a device to cause a code bar locking lever to continually function independently of the operation of a main bail without requiring alteration of the machine.

These and other objects are attained by the novel construction and arrangement of parts hereinafter described and illustrated in the accompanying drawings, forming a part hereof, and in which:

Fig. 1 is a perspective view showing the device applied to a typing reperforator;

Fig. 2 is an exploded view showing details of the device;

Fig. 3 is a view showing an element of the device engaging a code bar locking lever.

The view illustrated by Figure 1 is of a Model FPR-5H-193 typing reperforator, manufactured by the Teletype Corporation of Chicago, Illinois. The power for the performance of printing and other functions (except selection, perforating and spacing) is derived from the main bail 12, which is controlled, through intermediate levers, by a main bail cam 19 mounted on the main shaft 13. The main bail is designed to periodically move up and down. On the down stroke the main bail engages the projecting portion 16 of the code bar locking lever 17 to move the latter from engagement with the code bars 18 so that the code bars can be positioned by selecting mechanism to coincide with an incoming signal. On the up stroke the main bail 12 engages and raises a selected pull bar 14 to actuate a type bar 15 to print the selected character. Should the main bail 12 jam and not move up or down, the code bar locking lever will not be moved and the punch for perforating a tape will not be reconditioned in accordance with a desired new selection of the code bars. Printing telegraph apparatus of this general type has been described in the following U. S. Patents: No. 2,343,882; No. 2,255,794; No. 2,273,910; and No. 1,745,633.

In accordance with this invention, connections are made between the main bail cam 19 on main shaft 13 and the code bar locking lever 17 so the code bar locking lever will be periodically actuated independently of the movements of the main bail.

The main bail shaft 13 has two cams; one cam (not shown) which operates the punch bail arm 100; the other cam 19 which operates the main or printing bail 12. The main bail cam 19 is engaged by a cam roller 20 on cam lever 10 (these members being standard parts of a typing reperforator). Fixed to one end of cam lever 10 is an arm 6 having a slot 9 receiving a tongue 8 at the lower end of lever 4, which is pivotally mounted on the portion 7 of a bracket 5 attached to a member of the reperforator. The upper end of lever 4 is adjustably attached to a bar 3 by means of a screw 21. Adjustably attached to bar 3 by means of a screw 22 is a twisted bar 2 having a recess 23 receiving the upper end of code bar locking lever 17. Once elements 2 and 3 are positioned, the screw 22 ties them together and they operate as a single element for the purposes of this invention. The lever 4 is constantly urged in one direction by a spring 11 attached to the lever and to a member of the reperforator.

In operation, the main bail cam, (which normally operates the main bail) engages roller 20 to continually oscillate the cam lever 10, and through arm 6, lever 4, bar 3 and bar 2, continually move the code bar locking lever 17 into and out of engagement with the code bars.

It will be apparent to those skilled in the art that the main bail 12 can jam only in the "down" position, and in this position it will not "jam" anything else, particularly not the main bail shaft. When the main bail does jam it, therefore, will not interfere with the selector mechanism of the machine, nor with the code bar selection. When the main bail jams, ordinarily the code bar locking lever 17 locks out the punching mechanism from punching out the message. The object of this invention, therefore, is to provide a means 2 for pushing the code bar locking lever 17 back and forth in synchronism with the action of the bail cam 19 through the action of cam lever 10 and the means provided by the invention. In other words, a means is provided which bypasses the main bail cam and continues to oscillate the code bar locking lever in synchronism thus permitting the punching operation to continue after the main bail jams.

The main shaft 13, with the main bail cam fixed thereto, continually rotates, and consequently, cam lever 10 will continually oscillate regardless of the condition of the main bail. Thus continuous actuation of the code bar locking lever is insured.

From the above description it will be seen that there has been provided a simple and effective attachment for insuring continuous perforation of the tape in a reperforator at all times, even when the main bail jams and printing of characters on the tape is prevented. The above description is to be considered as illustrative and not limitative of the invention of which modifications can be made without departing from the scope as set forth in the appended claims.

The invention having been described, what is claimed is:

1. In a typing reperforator machine having at least a main bail, a main bail cam, a main bail mechanism actuated by said main bail cam for operating the main bail, a cam lever actuated by said main bail cam, and a code bar locking lever, means for bypassing the action of the main bail comprising a lever pivotally mounted on a bracket which is attached to a fixed part

of the machine, an arm attached to said lever and loosely engaging one end of the cam lever and actuated thereby, a bar attached to the other end of said lever, an extension of the bar adapted to engage the code bar locking lever of the machine, and a guide for the extension, whereby said locking lever is oscillated in synchronism with the main bail.

2. In a typing reperforator machine having at least a main bail, a main bail cam, a main bail mechanism actuated by said main bail cam for operating the main bail, a cam lever actuated by said main bail cam, and a code bar locking lever, means for bypassing the action of the main bail comprising a lever pivotally mounted on a fixed part of the machine, an arm attached to said lever and loosely engaging one end of the cam lever and actuated thereby, a bar attached to the other end of said lever, an extension on the bar adapted to engage the code bar locking lever, and a guide for the extension, whereby said locking lever is oscillated in synchronism with the action of the main bail cam.

3. In a typing reperforator machine having at least a main bail, a main bail cam, a main bail mechanism actuated by the main bail cam for operating the main bail, a cam lever also actuated by the main bail cam, and a code bar locking lever, means for bypassing the action of the main bail comprising a lever pivotally mounted to a fixed part of the machine having one of its ends in loose engagement with the cam lever, a bar attached to the other end of said lever having means for engaging said code bar locking lever, and spring means to normally urge the lever in one direction, whereby the code bar locking lever is caused to move in synchronism with the action of the main bail cam.

4. An attachment for a typing reperforator machine having a main bail cam, a cam lever actuated by said cam, and a code bar locking lever, comprising a bracket attached to a fixed part of the machine, a lever pivotally mounted on said bracket, means on the cam lever to actuate said lever, a bar connected to the lever, and means on the bar to engage the code bar locking lever of the machine for operating it in synchronism with said cam lever oscillations.

5. An attachment for a typing reperforator machine having a main bail cam, a cam lever actuated by said cam, and a code bar locking lever, comprising a lever pivotally supported by a fixed part of the machine, means on the cam lever engaging one end of the lever to actuate the latter, a bar attached to the other end of the lever having means to engage the code bar locking lever to oscillate it in synchronism with the movements of the cam lever, and spring means to normally urge the lever in one direction.
